FLARE DRILL

William E. Coyle, Cotton Valley, La.

Application July 31, 1950, Serial No. 176,878

4 Claims. (Cl. 255—76)

1

This invention relates to an expansion drill particularly suited for expanding drill holes in oil, water, or gas formations.

One important object of the present invention is to provide a drill of the type stated expandable within the drill hole in a manner to drill out larger openings in productive formations.

Another object is to provide a drill of the character described expandable by pressure applied through the medium of a piston, and equipped with a means for relieving said pressure when the drill cutters hang up on the wall of the drill hole or are receiving too much pressure.

Another important object is to provide a drill of the character described wherein the pressure applied through the medium of the piston causes normally flattened longitudinally extended spring cutters to be bowed outwardly radially of the drill in a manner to engage and enlarge the wall of the previously drilled hole.

With the foregoing and other objects in view which will appear as the description proceeds, the invention consists of certain novel details of construction and combinations of parts hereinafter more fully described and pointed out in the claims, it being understood that changes may be made in the construction and arrangement of parts without departing from the spirit of the invention as claimed.

Referring to the drawings

Figure 1 is a side elevational view of a drill formed in accordance with the present invention, the cutters being illustrated in their straightened or inoperative position.

Fig. 2 is a similar view, the cutters being bowed outwardly to operative position.

Fig. 3 is an enlarged section taken substantially on line 3—3 of Fig. 1.

Fig. 4 is an enlarged longitudinal section through the lower portion of the drill, portions being broken away.

Fig. 5 is a section taken on line 5—5 of Fig. 4.

Fig. 6 is a section on line 6—6 of Fig. 3.

Fig. 7 is a section on line 7—7 of Fig. 4.

Fig. 8 is a section on line 8—8 of Fig. 3.

Referring to the drawings in detail, a piston cylinder 1 is threaded at its upper end for connection to a pipe section 2, said pipe section being the lowermost section of the drill pipe which, as will be understood, extends upwardly to the surface.

Reciprocable within the piston cylinder 1 is the piston 3 and overlying the piston is the

2

washer valve 4 having the diametrically opposed slotted openings 5 which are adapted to be brought into and out of register with diametrically opposed circular openings 6 formed in the piston.

As illustrated in Fig. 6 the walls of these openings 5 are elongated and the side walls thereof converge so that the openings taper in opposite directions.

10 Extending through the center of the piston is a hollow shaft 7 on which the piston has up and down sliding movement when the piston slides upwardly and downwardly within the piston cylinder 1. The upper end portion 15 of the shaft 7 has the elongated longitudinal keyway 8, for the reception of a tongue 4' carried by the washer valve 4, which slides upwardly and downwardly with the piston, but is held against rotation relative to the hollow shaft. 20 The piston itself, however, can rotate relative to said hollow shaft.

The lower end of the piston is formed as a pressure plate 9, and connecting the top end of said piston 3 to said pressure plate 9 is the 25 cylindrical side wall 10 defining a hollow chamber with the piston and the pressure plate. A tubular shaft 7 extends through the piston 3 and the pressure plate 9 axially through the chamber and the bore of the shaft is an opening 11 formed in the shaft.

30 Diametrically opposed longitudinal slots 12 are provided in the lower end portion of the cylinder 1 and sliding in these slots are outwardly extending diametrically opposed lugs 13 carried by the pressure plate 9. The lugs 13 bear against a spacer sleeve 14 that surrounds the lower end of the cylinder 1. Therefore, downward movement of the piston carries with it the spacer sleeve 14. The lower end of the cylinder 1 has an annular inturned flange 15 on which seats an octagonal plate 16 which is threadedly connected to the lower end of the hollow shaft 7 and carries a depending hollow circular sleeve 17.

45 Surrounding the sleeve 17 is a torque spring 18, one end of which is engaged by a depending lug 19 carried by the lower end of the cylinder 1. The other end of the spring 18 abuts an outwardly extending lug 20 carried by said sleeve 50 17 carried by the sleeve and depending from the lower end thereof is a hollow drive shaft 21 which is square in cross section. Slidable on the portion of the shaft 21 adjacent the sleeve 17 is a movable upper collar 22 having a plurality of pairs of ears 23 here shown as four in

number. A fixed bottom collar 24 is rigidly secured to the lower end of the shaft 21 and has ears 25. Extending between the ears 23 are connecting pins 26 on which are pivotally mounted the upper ends of elongated longitudinally extended cutters 27 of spring material having the cutting teeth 28 formed on their outer surfaces. The lower ends of said cutters are pivoted upon cross pins 29 extending between the ears 25.

Spaced from top to bottom of the hollow drive shaft 21 are fluid circulation openings 30, that are continuously open. A bottom circulation opening 31 is normally closed by a ball valve 32, mounted upon the pivoted arm 33, which is pivotally mounted intermediate its ends upon the lower end portion of the shaft 21. To the other end of the arm 33 is pivotally connected the valve release rod 34 extending longitudinally adjacent the shaft 21, and slideable at its other end in the collar 36 secured to an intermediate portion of said shaft. Spring 35 surrounds the upper end of said valve release rod 34, and normally holds the ball valve 32 seated in position to close the opening 31.

In use, the drill is lowered into a previously drilled small drill hole, with the cutters in the position shown in Fig. 1 and the openings 5 and 6 in the washer valve 4 and piston 3 out of registry. When it is desired to begin expanding the drill hole, fluid pressure is applied through the drill pipe sections to the top of the cylinder 1. While the drill pipe 2 and the cylinder 1 are being rotated. Since the cylinder 1 is being rotated, the piston will also be rotated with the cylinder since the lower end of the piston is provided with the lugs 13 that extend through slots in the cylinder 1. The piston, of course, also has up and down movement relative to said cylinder.

As the piston moves downwardly, the lugs 13 will press downwardly the spacer sleeve 14 which, it may be noted, is not rotated directly by the cylinder 1. The lower end of the spacer sleeve 14 bears against the upper collar 22 to which the upper ends of the springable cutters 27 are connected. This forces the collar 22 downwardly. As a result, the cutters 27 will be bowed outwardly as in Fig. 2, and will expand into contact with the walls of the opening to be expanded, and the cutters 28 will then scrape away the sides of said drill hole, thus to expand the hole substantially.

As will be appreciated, the outwardly bowed cutters 27 rotate for the purpose of expanding the drill hole. In this connection, it may be noted that rotation of the cylinder 1 causes rotation of the spring 18 by reason of the lug 19 of the cylinder that engages the upper end of the spring. The spring 18 will in turn engage the lug 20 on the upper end of the drive shaft 21, rotating said drive shaft and, as a result, the cutters 27. During normal operation of the device, the piston will be forced downwardly and will be held in its lower position by the pressure thereupon, permitting regular operation of the drill. However, assuming that the cutters 27 might hang up upon some obstruction encountered thereby, resistance to rotation initiated by the hung cutters will be transmitted by the lug 20 to the spring 18 causing the spring to yield. Continued rotation of the cylinder 1 causes the spring 18 to transmit rotary motion to the hollow shaft 7 by way of the lug 19 and as a result, the washer valve 4 will rotate relative to the piston 3 so as to bring the large portions of the slot 5 of the washer valve 4 into registry with the openings 6 of the piston. The pressure upon the piston will be thereby relieved

as the fluid may escape through the openings 6 in the upper end of the piston into the chamber and thence downwardly through the opening 11 in the hollow shaft 7 and into the well hole through the slots 12 and the fluid circulation openings 30 of the drive shaft 21.

Relief of pressure upon the piston immediately causes the piston to move upwardly, flattening out the cutters 27 so that the cutters 27 are freed from any obstruction on which they may have become hung.

It will be understood that the reason for forming the slots of the washer valve as illustrated is to allow the flow of fluid through the registering slots and piston openings to become larger as the hollow shaft moves into position where the slots and openings begin to register.

In the upper end of the hollow shaft 7 is mounted a check valve 37, which allows circulating fluid to pass downwardly through the hollow shaft and through the circulation openings 30 when the device is not rotating, thus to permit clearance of or circulation of the cuttings to allow for further rotation of the tool. The check valve opens above a predetermined pressure.

Referring to the ball valve 32, this is opened whenever the collar 22 is moved downwardly to a position in which it will engage the upper end of the valve release rod 34. As a result, the ball valve 32 is lifted off its seat, so that pressure is directed through the bottom opening so as to clear the drill hole immediately below the device for further use of the device.

What is claimed is:

1. In an expansion drill for enlarging a well hole below the surface of the ground said drill being of the type employing elongated cutters adapted to be bowed outwardly into contact with the wall of a well hole and rotated in contact therewith, means for rotating said cutters and bowing them into contact with the wall of the well hole comprising, a cylinder adapted to be rotated within a well hole, a piston working within said cylinder and operatively connected to the cutters for bowing them outwardly as it advances within the cylinder, means for introducing fluid under pressure into said cylinder to advance the piston, a pressure relief valve carried by the piston, yielding means carried by the cylinder and operatively connected to the cutters for establishing rotary driving connection between the cylinder and the cutters, and means operatively connected to the cutters and to the pressure relief valve for opening said valve and permitting the escape of fluid from the cylinder when the resistance of the cutters to turning attains a predetermined value.

2. The structure recited in claim 1 in which the piston has openings extending longitudinally therethrough, the pressure relief valve comprises a disk mounted on the piston to rotate about the longitudinal axis thereof, and said disk has openings extending therethrough which in one position of the disk register with the openings in the piston.

3. In an expansion drill, an elongated fluid pressure conduit mounted to rotate about its longitudinal axis within a well hole, a piston mounted in the conduit to move longitudinally and to rotate therewith adjacent the end thereof adjacent the bottom of the well hole, a cutter drive shaft carried by the conduit for rotation relative thereto, said drive shaft projecting longitudinally from the conduit toward the bottom of the well hole, a collar carried by the cutter

drive shaft for movement longitudinally thereon adjacent the conduit, circumferentially spaced outwardly bowable cutters carried by the cutter drive shaft and connected to the collar, a torsion spring carried by the drive shaft and operatively engaging the conduit and the drive shaft for rotating the drive shaft when the conduit is rotated, means carried by the collar and operatively connected to the piston for moving the collar longitudinally on the drive shaft and bowing the cutters when fluid entering the conduit exerts pressure on the piston, a pressure relief valve carried by the piston, and means operatively connected to the drive shaft and to said pressure relief valve for opening said valve and permitting the escape of fluid pressure from the conduit when resistance to the turning of the drive shaft by the spring attains a predetermined value.

4. In an expansion drill for enlarging a well hole below the surface of the ground, an elongated cylinder mounted in the well hole for rotation about its axis, an elongated cutter drive shaft carried by the cylinder and projecting longitudinally therefrom, said cutter drive shaft being rotatable relative to the cylinder about the axis thereof, a piston mounted within the cylinder for movement under the influence of fluid pres-

sure within the cylinder, circumferentially spaced outwardly bowable cutters carried by the drive shaft and operably connected to the piston, said cutters being adapted to be bowed outwardly as the piston advances toward the cutter drive shaft under the influence of fluid pressure within the cylinder, a pressure relief valve carried by the piston and operatively connected to the cutter drive shaft for permitting the escape of fluid from the cylinder when the cutters resist turning, and yielding means carried by the drive shaft and operatively engaging the cylinder for yieldingly holding the valve closed and establishing driving connection between the cylinder and the drive shaft.
